HOWARD W. MATHESON, OF SHAWINIGAN FALLS, QUEBEC, CANADA, ASSIGNOR TO
CANADIAN ELECTRO PRODUCTS COMPANY LIMITED, OF MONTREAL, QUEBEC,
CANADA.

APPARATUS FOR THE MANUFACTURE OF ACETIC ACID.

Application filed March 15, 1919. Serial No. 282,883.

To all whom it may concern:

Be it known that I, HOWARD W. MATHESON, a subject of the King of Great Britain, and resident of the town of Shawinigan Falls, in the Province of Quebec and Dominion of Canada, have invented certain new and useful Improvements in Apparatus for the Manufacture of Acetic Acid, of which the following is a full, clear, and exact description.

This invention relates to improvements in apparatus for the manufacture of acetic acid from acetaldehyde, and the object of the invention is to provide a highly efficient, simple and inexpensive apparatus for the manufacture of acetic acid.

According to the invention, the aldehyde is oxidized in a kettle at suitable pressure and temperature and the vapors rising from the vessel are led through condensers and then returned into the vessel for further oxidizing.

In the drawings which illustrate the invention;—

Fig. 1 is a side elevation of the apparatus.
Fig. 2 is a plan view.

Fig. 3 is an elevation of the condensers.

Referring more particularly to the drawings, 11 designates a suitably shaped vessel having a lining of aluminum or other suitable material proof against the action of acetic acid in presence of oxygen and which furthermore does not act as a catalyst in the decomposition or oxidation of aldehyde. This kettle is provided at the top with a man-hole 12 and at the bottom with a discharge valve 13. The vessel or kettle contains pipe coils of material having the same characteristics as the lining. It is preferred, in order to facilitate temperature regulation, to employ two coils designated 14 and 14^a which are supplied with water from a main 15 through pipes 16, the flow being regulatable by valves 17. A valve controlled connection 18 is provided by means of which steam may be introduced into one of the coils. The coils have individual outlet pipes 19. A valve controlled pipe 20 is provided for introducing acetaldehyde into the kettle and a second valve controlled pipe 21 containing a Venturi meter 22 is provided for introducing air into the kettle. This pipe extends to the bottom of the kettle and is arranged in a spiral coil 23, which is provided with a multitude

of perforations permitting the air to escape over substantially the whole bottom area, so that it will bubble up and be distributed uniformly through the aldehyde and will also blow on the catalyst lying on or near the bottom of the kettle and keep the catalyst in suspension until complete solution of the catalyst occurs. With a kettle bottom of the shape shown and a pipe coil the perforations are preferably on the lower side of the coil to direct air downwardly and toward the bottom of the kettle, but as the direction of the jets is primarily to avoid collections of sediment the actual direction must be such as to obtain this result. At the top of the kettle is a valve controlled inlet 24 having a funnel-shaped mouth 25 into which the necessary charges of catalyst may readily be poured. The kettle is provided with a pressure gauge 26, a fluid level gauge 27 and an indicating or recording thermometer 28. At the top of the kettle is an outlet 30 for acetic vapors and also a safety valve 31 from which a pipe leads out of the building containing the apparatus. About mid-way between bottom and top, the kettle is provided with an inlet 32 for return of a mixture of acetaldehyde and acetic acid. It will be noted that wherever practicable all the connections to the kettle are at the top in order to avoid leakage of acid. In connection with each kettle is a water condenser 33 and a brine condenser 34. The water condenser is supplied with cold water through a pipe 35 and the warm water escapes through a pipe 36. The brine condenser is supplied with cool brine through a pipe 37 and the discharge is through a pipe 38. The interior arrangement of these condensers may be of any suitable type. The outlet 30 of the kettle is connected by a pipe 39 with the top of the condenser 33. Near the bottom of the condenser 33 is a valve controlled pipe 40 which leads into the upper part of the brine condenser. A valve controlled branch 41 from this pipe leads to a pipe 42 through which vapors may be passed to a scrubber (not shown). Near the lower part of the condenser 34 is a valve controlled connection 43 leading into the pipe 41. By this arrangement, the condensed vapors from the water condenser may be turned directly into the scrubber line 42 and the brine condenser 34 completely short-circuited in case of a break down. A pipe 44

leads from the bottom of the condenser 33 to draw off the condensation products and a similar pipe 45 leads from the bottom of the brine condenser 34. A valve controlled connection 46 is established between these pipes at the level of the condenser bottoms. The lower ends of the pipes 44 and 45 connect with a U-shaped pipe 47 leading to the inlet 32 of the kettle. This new pipe extends 10 downwardly a sufficient distance and the condensers are sufficiently elevated with respect to the kettle, so that the pipe forms a liquid seal between the kettle and condensers preventing the liquid in the kettle discharging through the pipes 44 and 45 into the condensers but enabling the condensers to discharge into the kettle. It is obvious that since there is direct connection between the top of the kettle and the top of the condensers 15 pressures in the kettle and condensers will be substantially equal. Connected to the outlet 13 is a valve controlled pipe 48 leading to any suitable acid storage and also a valve controlled pipe 49 leading to a sewer. An adjustable relief valve 50 is provided in the pipe 41 which acts automatically if the pressure passes a predetermined point to relieve the pressure by discharge 20 into the scrubber line 42.

30 The operation of the device is as follows:—

The kettle is charged with aldehyde through the pipe 20, the level of liquid being indicated by the gauge 27. The aldehyde line is closed. A suitable amount of catalyst is poured into the kettle through the funnel 25 and the valve 24 is closed. Steam is admitted through the pipe 18 to the inner coil 14^a to raise the temperature of the aldehyde to a point at which the reaction will take place satisfactorily. The steam is turned off and air is admitted in suitable quantity through the pipe 21. This air bubbles up from the bottom of the tank through 40 the hot aldehyde and a certain amount of the aldehyde is oxidized into acetic acid. The reaction is accompanied with a considerable evolution of heat which is absorbed by passing water through either or both of the coils 14, 14^a, the amount of water being 45 regulated as desired. Owing to the temperature of the reaction, a certain amount of the aldehyde and the formed acetic acid are vaporized and pass through the pipe 39 to the water condenser 33. Vapor which does not condense in the water condenser is passed through the pipe 40 to the colder brine condenser or in an emergency may be 50 passed through the pipes 40 and 41 directly to the main 42 leading to the scrubber. Any vapor not condensed by the brine condenser may be passed through the connection 43 into the pipe 41 and thence to the scrubber. The condensation products of the condensers 55 are returned through the pipes 44 and 45

and the U-seal 47 into the reaction vessel 11. This condensation product is a solution of acetic acid in aldehyde, the strength of the solution gradually increasing as the process continues. It will thus be seen that the circulation will continue in the apparatus as long as a suitable temperature is maintained in the reaction vessel. The temperature is gauged by the thermometer and is controlled by regulating the admission of water to the coils 14, 14^a. The pressure is controlled primarily by regulating the admission of air and indirectly by the temperature and secondarily by adjustment of the relief valve 50. Any unforeseen rise in temperature which is not relieved through the valve 50 may be relieved through the safety valve 31 before damage is done to the apparatus. The pressure will in all cases be regulated to keep the boiling point of the aldehyde well above the temperature used. As the reaction continues, more and more of the aldehyde becomes converted into acetic acid. When the acid solution reaches the desired degree of concentration, the admission of air is stopped and the reaction consequently stops. The temperature is lowered by continued circulation of cold water through the coils so that no more vapor passes to the condensers. The drain outlet 49 is closed and the kettle outlet 13 opened, so that the acid flows away through the pipe 48 for storage. The pipe 48 is then closed, the drain 49 opened and the kettle washed out preparatory to the insertion of a new charge.

Having thus described my invention, what I claim is:—

1. An apparatus for the manufacture of acetic acid from acetaldehyde, comprising a reaction vessel, an air pipe leading to the bottom of said vessel, said pipe being provided with means for directing air against the bottom of the vessel, means for adjusting and for gaging the flow of air through said pipe, a pair of temperature controlling coils located in the reaction vessel, means for admitting a heating agent to one of said coils and for admitting a cooling agent to both coils, a pair of condensers connected in series for the passage of vaporous and gaseous products from the reaction vessel and connected in parallel for return flow of condensate to the reaction vessel, a U-seal in the return between said condensers and the reaction vessel, a by-pass conduit for short-circuiting one of said condensers, a valve for isolating the return flows of the condensers, and a pressure regulating gas discharge valve at the discharge end of the condenser series beyond the by-pass.
2. An apparatus for the manufacture of acetic acid from acetaldehyde comprising a reaction vessel, an air pipe leading to the bottom of said vessel and provided with means for directing air against the bottom

of the vessel, means for adjusting and gauging the flow of air through said pipe, a temperature controlling coil located in the reaction vessel, means for admitting a heating agent to said coil, means for admitting a cooling agent to said coil, a reflux condensing apparatus connected with the reaction vessel, means for preventing flow of liquid from the reaction vessel to the condenser, and a pressure regulating device at the discharge end of the condensing apparatus being an adjustably loaded escape valve for gas.

3. An apparatus for the manufacture of acetic acid from acetaldehyde comprising a reaction vessel, an air pipe leading to the bottom of said vessel and provided with means for directing air against the bottom of the vessel, means for adjusting and gauging the flow of air through said pipe, a temperature controlling coil located in the reaction vessel, means for admitting a heating agent to said coil, means for admitting a cooling agent to said coil, a reflux multi-stage condensing apparatus connected to the reaction vessel, said condensing apparatus having condensate returns for the several stages thereof, means to prevent flow of liquid from the reaction vessel to any stage of the condenser, means to by-pass a stage of the condensing apparatus, means to isolate the liquid discharge of such by-passed

stage from the reaction vessel and from the rest of the condenser, and a pressure regulating means disposed beyond the last stage of the condensing apparatus and adapted to control escape of gas from the system.

4. An apparatus for the manufacture of acetic acid from acetaldehyde comprising a reaction vessel, an air pipe leading to the bottom of said vessel and provided with means for directing air against sedimentary matter disposed upon or near the bottom of the vessel to maintain the bottom of the vessel substantially clear of such sedimentary matter and to maintain the matter in suspension in the liquid contents of the vessel, means for adjusting and gauging the flow of air through said pipe, means located in the vessel for heating or cooling the contents thereof, means for admitting heating or cooling agents to the heating or cooling means, a reflux condensing apparatus connected with the reaction vessel, means for preventing flow of liquid from the reaction vessel to the condensing apparatus, and a pressure regulating device at the discharge end of the condensing apparatus serving to control escape of gas from the system.

In witness whereof, I have hereunto set my hand.

HOWARD W. MATHESON.
